ASH TRAY

Robert N. Baylis, Caldwell, N. J., assignor to
 Smokador Manufacturing Co., Inc., Bloomfield,
 N. J., a corporation of Delaware

Application April 26, 1939, Serial No. 270,102

4 Claims. (Cl. 131—240)

This invention relates to certain improvements in ash trays and receptacles.

The object is to provide a simple and effective holder or rest for cigars or cigarettes, which rest also functions as a handle to lift the receptacle and also as a guard or screen to prevent improper waste material, such as paper, from being deposited in the tray and plugging up the discharge opening leading from said tray to the waste receptacle proper on which the tray is mounted.

In the drawing—

Fig. 1 is a plan view; and

Fig. 2 is a side elevation partly in section of the parts shown in Fig. 1, including a portion of the waste receptacle on which the tray is mounted.

1 represents the upper part of a waste receptacle for containing smokers' waste, such as ashes, cigarette and cigar butts and the like. 2 represents a tray which is dished and provided with a central discharge passage 3, through which smokers' waste is designed to pass on its way to the receptacle 1. For the effective use of the tray it is essential that this aperture shall be kept open and hence it is desirable to provide means to prevent papers, such as cigarette wrappers, from being deposited in the tray proper so as to cover or plug the outlet 3. In the particular instance shown the receptacle 2 is detachably connected to the lower side of the tray by any suitable means, such as a screw thread connection 4. The present invention is confined to the guard or screen means and this, in its preferred form, is so constructed that it not only acts as a screen but also as a handle to permit the assembled receptacle and tray to be lifted, and also as an efficient support or rest for lighted cigars or cigarettes, holding them in such a position over the tray that they will not drop on the floor when burned back.

40 The guard is shown in the drawing in its preferred form and is made of a single piece of wire, bent into a sort of star-shaped formation so as to provide a plurality of radially arranged looped arms or lobes 5—5 and 5'—5' radiating from an open center. The ends of this wire meet at the outer bend of one of the lobes or arms 5. The sides of each lobe 5 are preferably about parallel to each other and spaced apart sufficiently to permit a lighted cigar to be safely rested lengthwise thereon above and radially of the dished portion of the tray, so that ashes dropping therefrom will fall directly into or close to the discharge outlet 3. The other lobes or arms 5'—5' are somewhat shorter than the lobes 5—5 and are positioned between the latter. The sides of each of these

arms 5'—5' are also substantially parallel and somewhat closer together than the sides of the arms 5—5, the spacing being such as to safely support a lighted cigarette lengthwise thereon with the lighted end near the center of the tray. Just inside the rim of the tray I provide a recessed portion, preferably formed by an annular groove 6 facing inwardly or toward the center of said tray and of a size to snugly receive the wire bends at the ends of the lobes 5—5. The length of the arms 5—5 is such that they may be sprung into said recessed portion of the tray by a slight deformation of the screen, so that the inherent resiliency of the wire may be relied upon to firmly, yet detachably, connect the screen to said tray. This will permit the screen to be engaged by the fingers and used as a handle to lift the tray and receptacle. The intermediate lobes or arms 5'—5' are made shorter than the lobes or arms 5—5, so that in applying the screen it requires that the latter only be engaged with the tray, thus simplifying the operation. This construction also assures, in the preferred form shown, a uniformly spaced three-point engagement of the screen with the tray, whereby the screen may be easily removed or freed by collapsing the screen only sufficiently to dislodge the end of only one of the lobes 5—5 from the groove 6, whereupon the screen may be removed by merely tilting the same. By having the ends of the wire abut at the outer end of one of the lobes 5 the walls of the groove will prevent said ends from slipping by each other. In practice the spaces between the screen lobes are not large enough to permit pieces of paper, too large to pass freely through the passage 3 and carelessly deposited on the screen, from entering the tray and outlet.

From the foregoing it will be seen that the guard described functions not only as a screen for the tray but also as a handle and also as a most effective rest for lighted cigarettes and cigars, holding the latter radially of the tray center and so far in toward the center that danger of their falling off onto the floor or floor covering is practically eliminated.

I claim:

1. An ash tray having a circumferentially extending generally inwardly opening annular groove therein near the outer rim, and a generally radially compressible screen formed of bent wire and providing a plurality of radially extending arms of different lengths for supporting cigars and cigarettes, the ends of the longer arms fitting into said groove for resiliently holding said screen on said tray against displacement.

2. An ash tray, and a screen, said screen comprising a single length of wire bent into the form of a plurality of radially arranged holding lobes and a plurality of shorter intermediate screening lobes, said wire being resilient, whereby said screen may be contracted in a radial direction, and said tray having holding means for engagement by said holding lobes when said screen is expanded for holding said screen in place.
- 10 3. An ash tray, a screen therefor comprising a length of wire bent to form a plurality of radially arranged screening and holding lobes and a plurality of shorter intermediate screening lobes, said wire being resilient whereby said screen may be bodily contracted in a radial direction, said tray having holding means for engagement by the ends of said first mentioned lobes when said screen is expanded, the sides of said lobes being
- 15

so spaced as to support cigars or cigarettes longitudinally thereon from the tray edge and toward the center thereof.

4. A screen for an ash tray of the type having inwardly directed screen holding means adjacent its upper inner edge, said screen comprising a wire bent to form a plurality of radially extending lobes of different lengths, the sides of certain of said lobes being spaced sufficiently to support cigarettes longitudinally thereon and radially of 10 said tray, other of said lobes being spaced more widely than the sides of the first mentioned lobes and sufficiently to support cigars lengthwise thereon and radially of said tray, said screen being collapsible radially to permit certain of said 15 lobes to engage with said tray holding means to hold the screen in place.

ROBERT N. BAYLIS.
